(57) **CLAIM**

We claim the ornamental design for a dispenser assembly, as shown and described.

DESCRIPTION

FIG. 1 is a front perspective view of a dispenser assembly showing our new design;

FIG. 2 is a rear perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken lines in the drawings showing the dispenser assembly illustrate the portions of the dispenser assembly that form no part of the claimed design.
